UNITED STATES PATENT OFFICE.

SIMON SNYDER, OF MUNCY, PENNSYLVANIA, ASSIGNOR TO SPROUT, WALDRON & CO., OF MUNCY, PENNSYLVANIA, A CORPORATION OF PENNSYLVANIA.

FEEDING AND MIXING MACHINES CONNECTED IN GANGS.

Application filed October 18, 1924. Serial No. 744,503.

To all whom it may concern:

Be it known that I, SIMON SNYDER, a citizen of the United States, residing at Muncy, in the county of Lycoming and 5 State of Pennsylvania, have invented certain new and useful Improvements in Feeding and Mixing Machines Connected in Gangs; and I do hereby declare the following to be a full, clear, and exact description 10 of the invention, such as will enable others skilled in the art to which it appertains to make and use the same.

This invention relates to feeding and mixing machines such as are used in flouring 15 mills, for feeding and mixing different kinds of grain or granulated materials in predetermined desired proportions.

Machines of the character referred to have heretofore been connected in gangs operated by the same driving shaft, each machine having associated therewith mechanism for changing its speed, so as to increase or decrease the amount of quantity of grain or stock to be delivered by each individual 25 machine, either directly to a grinder or into a common delivery or discharge spout, in such quantity as may be desired, without affecting any other machine in the group, together with means associated with one machine of the series whereby the speed of the entire group may be simultaneously changed, to increase or decrease the quantity of material discharged from each individual machine within a given period of time, without 30 changing or affecting the proportional amount which the individual machines may have been initially set to deliver; or in other words, each one of a group of machines is provided with what is commonly known as 35 variable speed mechanism independently adjustable so that the adjusting mechanism on each machine may be initially set to effect the discharge therefrom of a given quantity of grain or stock at a given rate of speed; 40 one machine delivering so many quarts or gallons per minute and another machine the same or a greater or less quantity throughout the entire group, while one of the group of machines, usually the first, is provided 45 with mechanism whereby the speed of the entire group may be simultaneously changed so as to cause the individual machines to feed a greater or less quantity of material 50 in a given period of time without changing the proportional amount any machine may

have been initially set to deliver, regardless of the quantity delivered by other machines in the same group.

One object of the present invention is to provide an improved machine of the character referred to in which variable speed mechanism such as hereinbefore mentioned is dispensed with, and to provide simple and efficient means for effecting simultaneous operation of a group of such machines and 60 the delivery to a common mixing device by each machine of the group of a measured or given quantity of material in a given period of time, in greater or less quantity, as may be desired, and to enable the operator 65 to vary at will the proportional amount of material to be delivered by any one of the group of machines without affecting any other machine in the group.

A further object is to provide a simple, 70 efficient, inexpensive and dependable machine for feeding in measured or predetermined quantities granular material or stock feed, such as flour, corn meal and grain, either whole or granulated, as wheat or corn 75 and various kinds of stock feed, such as oats, bran, middlings, or ground alfalfa, and which machines may be connected in gangs, together with a mixing device common to 80 the entire group, whereby different kinds of 85 materials delivered by different machines in the group may be mixed, in either the same or different proportions, as desired, all in a continuous operation.

The invention will first be hereinafter 90 more particularly described, with reference to the accompanying drawings, which are to be taken as a part of this specification, and then pointed out in the claims at the end of 95 the description.

In said drawings, Fig. 1 represents a vertical sectional elevation of a machine embodying my invention; the section being taken on the line 1—1 of Fig. 3;

Fig. 2 represents a vertical sectional elevation taken on the line 2—2 of Fig. 3, or substantially at right angles to the section shown in Fig. 1;

Fig. 3 represents a top plan view;

Fig. 4 is a bottom plan view; the supporting frame and parts below the bottom being broken away;

Fig. 5 is a side elevation of a group of machines and associated mixing device, including a spiral conveyor, for mixing and

discharging the material fed by the group of machines into a suitable receiver; and

Fig. 6 is a detail sectional view taken on a line passing through the discharge port in 5 the hopper bottom and the registering opening in the adjustable feed regulating device or plate which underlie the path of movement of the conveyor arms on the periphery of the feed wheel.

10 In Figs. 1 to 4 I have shown a preferred form of embodiment of feed mechanism or feeding machines especially designed and adapted to be connected in gangs, for delivering grain and various food products in 15 variable predetermined proportions to a suitable mixing device, while in Fig. 5, I have shown a group of such feed mechanisms operably connected to a main driving shaft and to a rotary conveyor adapted for 20 the purposes of my invention, though other forms may be employed.

Referring to the drawings, in which the same reference characters are used to denote corresponding parts in different views, 25 the letter A denotes one of a group of machines, shown in Fig. 5, and denoted by the letters A, A¹, A² and A³, all of substantially the same construction and equipped alike, so that a description of one, the first 30 in the group, denoted by the letter A, and illustrated in detail in Figs. 1 to 4, will suffice for a description of each and all of the machines shown in the connected group, all of which are geared to and driven by 35 the same driving shaft. Each machine has a feed hopper preferably of cylindrical form and each provided with a bottom plate a mounted upon a frame B, said frames being provided with alined bearings in which 40 is journaled a driving shaft C. The hopper bottom has depending therefrom a tubular boss a¹ to provide a bearing for the vertical shaft D which has its lower end revolvably fitted in a step-box secured to the floor or 45 supporting base on which the machine rests. The shaft D has fixed thereon within the hopper a feed wheel F and slidably secured thereto underneath the hopper a skew bevel gear d, which meshes with a smaller skew 50 bevel gear or pinion c fixed on the shaft C for imparting rotary motion to the vertical shaft. The skew bevel gear d has a spline and groove connection or the like with the vertical shaft to adapt it to rotate with the 55 shaft while permitting it to be raised and lowered, as desired, for the purpose of throwing the machine into or out of operation without stopping or affecting the operation of any other machine in the group. 60 For the purpose of raising and lowering the gear wheel d a lever E is pivotally mounted on the machine frame and provided with a forked end e, which is pivotally connected with a collar e¹ engaging a groove in the 65 hub portion of the gear wheel so as to per-

mit rotation thereof unaffected by its connection with said lever. The feed wheel F has a hub portion f secured to the vertical shaft by means of a set screw f¹, to permit vertical adjustment of the feed wheel and 70 adapt the same to be removed to permit the substitution of a feed wheel having conveyor arms or pockets of greater or less depth or capacity than the one shown, for the purpose hereinafter described. G denotes an oscillatory feed regulating device which may consist of a circular or segmental plate resting on the hopper bottom, underneath the feed wheel and arranged to underlie the path of movement of a series of 75 radially projecting conveyor arms f² on the periphery of the feed wheel. The plate G has formed therein an oblong arcuate slot or opening g which is adapted to register with a correspondingly shaped opening forming a discharge port in the hopper bottom, at one side thereof, said registering openings being preferably formed with substantially V-shaped end-portions so that 80 by adjusting the oscillatory plate the discharge port may be reduced in size to a minute degree or considerably enlarged to decrease or increase the amount of material that may pass therethrough as desired in mixing materials of different kinds. A superposed annular plate or false bottom H is secured to the inner wall of the feed hopper, by means of fastening bolts or screws h inserted in oblong slots h¹ in the 85 cylindrical wall of the hopper and screwed into threaded holes in a peripheral flange h² on the periphery of said false bottom, so that when it is desired to make a change for feeding other material than that which is being fed by the particular feed wheel in 90 use at the time, said superposed plate may be removed and a feed wheel of greater or less capacity substituted, and the false bottom replaced and secured in either a raised or lowered position as desired to accommodate interchangeable feed wheels of different thicknesses in feeding materials of different kinds. The false bottom H has 95 formed therein at one side an oblong arcuate slot h³, Fig. 3, overlying an imperforate portion of the hopper bottom, or an imperforate portion of the oscillatory plate resting on said bottom, while an imperforate portion of said false bottom overlies the discharge port in the hopper bottom and the registering opening in the feed regulating plate. The central imperforate portion of the feed wheel is preferably slightly raised and underlies a central circular opening in the false bottom around which is 100 formed an upright marginal flange h⁴ and above said raised center there is secured on the vertical shaft D a cone-shaped or semi-globular deflector I, the lower edge or rim of which overlaps said circular flange 105 110 115 120 125 130

so as to prevent granulated material within the hopper from escaping around the center of the feed wheel; said deflector being adapted to direct such material outwardly 5 toward the inner wall of the hopper and upon an imperforate portion of the hopper bottom between adjacent radially projecting conveyor arms f^2 on the periphery of the feed wheel or into pockets in said periphery as said arms or pockets travel past the arcuate opening h^3 in the false bottom H. The conveyor arms preferably taper outwardly to an intermediate point from which point they are forwardly inclined in 10 the direction of rotation at an obtuse angle to the base so as to adapt them to more effectually push the material between adjacent arms of the feed wheel toward the outlet or discharge port, which lies underneath the imperforate portion of the false bottom and is concealed thereby. The deflector I has a tubular hub-like portion adapted to fit upon the vertical shaft D, to which it is adjustably and removably secured by means of a set screw i. Above the deflector is secured a rotary agitator K having a tubular hub-like end portion to fit upon the shaft D, to which it is adjustably and removably secured by a set screw k, 20 as shown. The depending rim or lower edge of the deflector is formed or provided with preferably equi-distant bosses on the lower edge thereof having interiorly screw threaded holes or sockets therein, in which are screwed agitator arms or pins L arranged close to the surface of the false bottom so as to sweep around the same and upraise and push the material resting on the imperforate portion thereof toward the discharge port, such pins being designed to be used in feeding and mixing certain kinds of material which may not be sufficiently agitated or stirred up by the agitator K. The hoppers are each provided with a removable top section N, of rectangular form, 30 having an upwardly and outwardly flaring portion n, which terminates in a vertical extension n^1 , and a pendant cylindrical portion n^2 , which is adapted to fit within the upper cylindrical end of the hopper proper or the body portion thereof, while the four corners of the rectangular portion rest upon the upper cylindrical end of the main or body portion of the hopper, whereby the 40 receiving end or mouth of the hopper is greatly enlarged, to adapt it to be more easily filled and avoid waste by overflow and to facilitate the flow of material therethrough. Loosely fitted upon the vertical shaft D, or upon the boss on the underside of the bottom plate in which said shaft has a bearing, is fitted a ring or collar on the inner end of a pointer arm O which is upheld by means of a collar o secured upon 45 said boss, by means of a set screw o^1 . The free end of said pointer arm carries a pointer o^2 adapted to travel along a graduated scale P on the hopper to indicate the quantity of material to be delivered by the machine when the free end of the pointer arm is moved by the movement of the feed regulating device or plate G, to which the free or outer end of said pointer arm is secured by means of a bolt and nut as shown at o^3 . The feed regulating plate has swiveled thereto on the underside thereof a pendant lug or boss i^1 which works in an arcuate slot in the bottom of the feed hopper, said lug having a threaded hole therein in which is screwed a threaded rod Q 50 which is revolvably secured to a bracket q on the outer wall of the hopper and provided at its free end with a disk q^1 having a milled periphery for rotating the rod by hand. As will be seen, when the oscillating plate G is adjusted the index finger or pointer carried by the arm O, which moves to and fro with said plate, will be moved into position to indicate the quantity of material that the machine will deliver during each revolution of the feed wheel, the quantity delivered being increased or diminished at will by adjusting said feed regulating device so as to increase or decrease the size of the discharge port in the hopper 55 bottom. The material discharged by the group of machines in the desired proportions is spouted or conducted into a subjacent trough-like receptacle R, in which is placed a spiral conveyor S, of ordinary or any suitable construction, adapted to be operated by belt and pulley connection with the main driving shaft C, as shown in Fig. 5, or by other suitable gearing, and the materials entering said conveyor trough are 60 thoroughly commingled and conveyed to a suitable receptacle therefor located at the delivery end of the conveyor, or at any convenient point, underneath or below a discharge spout, (not shown). The operation of the machine will be readily understood from the foregoing description taken in connection with the accompanying drawings. Any desired number of feeding machines may be connected and operated by the same driving shaft, for example, four, as shown in Fig. 5. The feed regulating devices of the individual machines are initially set to deliver a certain quantity of material in desired proportions during each revolution of the feed wheel, each machine delivering the amount indicated by the pointer on the scale plate, which may be more or less than or equal to the amount delivered by any other machine, 65 and the machines being set in motion, the material discharged into the conveyor trough by the group of machines in the same or different proportions will be thoroughly commingled by the conveyor and discharged 70 75 80 85 90 95 100 105 110 115 120 125 130

into a feed hopper or other receptacle therefor, on reaching a point at which the desired commingling has been effected.

Within the recess provided on the under-
5 side of the feed wheel by the central circular
step-like formation thereof there is placed a
collar d^1 which may be fixed on the shaft
D by means of a set screw or other fasten-
ing device, to prevent the raising of the
10 feed gate or feed regulating device or
plate G.

It will be understood of course that va-
rious changes may be made in the details
of construction and arrangement of parts
15 without departing from the spirit and scope
of my invention, and I therefore do not
desire to be limited to the specific construc-
tion and arrangement of parts shown and
described. I also desire it to be understood
20 that the expression "granulated materials,"
as used in the appended claims, is not in-
tended to be restricted to ground grain but
to include mixable materials of various
kinds, either whole or ground grain or the
25 like, used for the production of food or
stock and poultry feed and which it may
be desirable to mix in either equal or dif-
ferent proportions.

Having thus described my invention, what
30 I claim as new and desire to secure by Let-
ters Patent of the United States is:

1. In combination, a plurality of machines
for feeding granulated materials in prede-
termined proportions, each machine having
35 a feed hopper thereon provided in its bottom
with an elongated discharge port, means for
enlarging or decreasing the size of said port,
so as to increase or decrease the amount of
material discharged therethrough, a rotary
40 feed wheel overlying said bottom and carrying
means for conveying material to said
port successively in equal proportions, and a
superposed fixed plate or false bottom hav-
ing an elongated opening therein overlying
45 the path of movement of said conveyor
means at a point remote from said discharge
port, whereby the material within the hop-
per is delivered to said conveyor means upon
an imperforate portion of said bottom plate
50 and conveyed to said port; said feed wheel
being fixed on a vertical shaft extending up
through the hopper bottom and having a
gear wheel thereon below said bottom; said
machines being provided with alined shaft
55 bearings, a driving shaft journaled in said
alined bearings and carrying gear wheels in
mesh with the gears on said vertical shafts,
and means for mixing the materials dis-
charged from said machines and conveying
60 the mixture into a suitable receptacle there-
for.

2. In combination, a group of machines
each provided with a feed hopper having a
65 discharge port in its bottom, a rotary feed
wheel having means for conveying material

to said port successively in equal proportions,
a fixed plate overlying said bottom and hav-
ing a discharge opening therein overlying
the conveyor means on said feed wheel at a
70 point remote from said discharge port, an
oscillatory plate arranged between the hop-
per bottom and said feed wheel and having
an opening therein registering with said dis-
charge port, and means for adjusting and
75 securing said oscillatory plate in different
positions, so as to increase or decrease the
size of the discharge port, to adapt a group
of machines to deliver material to a mixing
device in either equal or different predeter-
80 mined proportions; each of said feed wheels
being fixed on a vertical shaft extending up
through the hopper bottom and carrying a
gear wheel below said bottom, and said ma-
chines having alined bearings thereon, a
85 driving shaft journaled in said alined bear-
ings, and means for conducting the materials
discharged by said machines into a common
receptacle, said receptacle containing means
for mixing and conveying the mixture into
90 a suitable receiver.

3. In combination, a group of machines
each provided with a feed hopper having an
elongated discharge port in its bottom, a ro-
tary feed wheel having means for conveying
95 material to said port successively in equal
proportions, a fixed plate overlying said bot-
tom and having an elongated opening there-
in overlying said conveyor means at a point
remote from said discharge port, an oscil-
100 latory plate arranged between the hopper
bottom and said feed wheel and having an
elongated opening therein registering with
said discharge port, means for adjusting and
securing said oscillatory plate in different
105 positions, so as to increase or decrease the
size of the discharge port at will, to adapt
the group of machines to deliver the ma-
terial discharged therefrom in either equal
or different predetermined proportions, each
110 of said feed wheels being fixed on a vertical
shaft extending up through the hopper bot-
tom and carrying a gear wheel below said
bottom, and said machines having alined
bearings thereon, a driving shaft journaled
115 in said alined bearings, and means for con-
ducting the materials discharged by the
several machines into a common receptacle
therefor; said receptacle containing means
for mixing and conveying the mixture into
120 a suitable receiver.

4. In combination, a group of machines
each provided with a cylindrical feed hopper
having an elongated arcuate discharge port
in its bottom, a rotary feed wheel having
means for conveying material to said port
125 successfully in equal proportions, a fixed
circular plate overlying said bottom and
having an elongated arcuate opening therein
overlying said conveyor means at a point re-
mote from said discharge port, an oscil-

latory plate arranged between the hopper bottom and said feed wheel and having an elongated arcuate opening therein registering with said discharge port, means for adjusting and securing said oscillatory plate in different positions, so as to increase or decrease the size of the discharge port at will, to adapt a group of machines to deliver the material discharged therefrom in either 10 equal or different predetermined proportions, each of said feed wheels being fixed on a vertical shaft extending up through the hopper bottom and carrying a gear wheel below said bottom, and said machines having 15 alined shaft bearings thereon, a driving shaft journaled in said alined bearings, and means for conducting the materials discharged by the several machines into a trough-like receptacle, said receptacle containing a spiral conveyor for mixing and conveying the mixture into a suitable receiver.

5. In combination, a gang of operatively connected machines for feeding granulated materials in predetermined proportions, each machine having a feed hopper provided in its bottom with an elongated discharge port, means for enlarging and decreasing the size of said port so as to increase or decrease the amount of material discharged therethrough, a rotary feed wheel overlying said bottom and having means for conveying material to said port successively in equal proportions, a superposed fixed plate or false bottom having an elongated opening therein overlying the path of movement of said conveyor means at a point remote from said discharge port, whereby the material is delivered to said 40 conveyor means upon an imperforate portion of said bottom and conveyed to said port; each of said feed wheels being fixed on a vertical shaft extending up through the hopper bottom and having a gear wheel thereon below said bottom and said machines being provided with alined shaft bearings, a driving shaft journaled in said alined bearings and carrying gear wheels in mesh with the gears on said vertical shafts, and means for mixing and conveying the materials discharged from said machines into a common receiver.

6. In combination, a gang of machines operatively connected and provided with means for supplying a mixing device with granulated materials in different proportions, each machine having a feed hopper provided in its bottom with a discharge port, means for enlarging and decreasing the size of said port so as to increase or decrease the amount of material discharged therethrough, a rotary feed wheel overlying said bottom and having means for conveying material to said port successively in equal proportions, and 60 a superposed fixed plate or false bottom hav-

ing an elongated opening therein overlying the path of movement of said conveyor means at a point remote from said discharge port, whereby the material is delivered to said conveyor means upon an imperforate portion of said bottom and conveyed to said port; each of said feed wheels being fixed on a vertical shaft extending up through the hopper bottom and having a gear wheel thereon below said bottom; said machines being provided with alined shaft bearings and said mixing device provided with a spiral conveyor, a driving shaft journaled in said alined bearings and carrying gear wheels in mesh with the gears on said vertical shafts, and means connecting said driving shaft with said spiral conveyor for operating the latter.

7. A machine for feeding granulated materials in predetermined quantities, comprising a feed hopper having a bottom plate provided with an elongated discharge port, means for enlarging and decreasing the size of said port so as to increase or decrease the amount of material discharged therethrough, a rotary feed wheel overlying said bottom and having means for conveying material to said port successively in equal proportions, and a superposed fixed plate or false bottom having an elongated opening therein overlying the path of movement of said conveyor means at a point remote from said discharge port, whereby the material is delivered to said conveyor means upon an imperforate portion of said bottom plate and conveyed to said port.

8. A machine for feeding granulated materials in predetermined quantities, comprising a feed hopper having a bottom plate provided with a discharge port, rotary conveyor means overlying said bottom plate, a superposed fixed plate or false bottom having an elongated opening therein overlying the path of travel of said conveyor means at a point remote from said discharge port, whereby the material within the hopper is delivered to said conveyor means upon an imperforate portion of said bottom plate and conveyed to said port, and means for enlarging and decreasing the size of said port so as to increase or decrease the amount of material discharged therethrough.

9. A machine for feeding granulated materials in predetermined quantities, comprising a feed hopper having in its bottom an elongated discharge port, a rotary conveyor arranged over said bottom and having radially projecting conveyor arms, said port underlying the path of movement of said arms, whereby a predetermined quantity of material within the hopper is deposited between adjacent arms successively upon an imperforate portion of said bottom and conveyed to said discharge port, and means for enlarging and decreasing the size

of said port so as to increase or decrease the amount of material allowed to pass therethrough at will.

10. A machine for feeding granulated material in predetermined quantities, comprising a cylindrical feed hopper having in its bottom an elongated discharge port, a rotary circular plate having on its periphery radially projecting conveyor arms, the outer 5 portions of which extend at an angle to the major or base portions thereof from a point about midway of their length to their free ends, said port underlying the path of movement of said arms, a superposed circular 10 plate or false bottom fixed to the inner wall of said hopper and having an elongated opening therein overlying the path of movement of said arms at a point remote from said discharge port, whereby a predetermined 15 amount of material within the hopper is deposited between adjacent arms successively upon an imperforate portion of said bottom and conveyed to said discharge port, and means for enlarging and decreasing 20 the size of said port so as to increase or decrease the amount of material allowed to pass therethrough at will.

11. A machine for feeding granulated materials in predetermined quantities, comprising a feed hopper having a discharge port in its bottom, a rotary conveyor fixed on a shaft above said bottom having means located beside the inner wall of the hopper 30 for conveying material within the hopper to said discharge port, a superposed fixed plate or false bottom having an elongated opening therein overlying the path of travel of said conveyor means at a point remote from said discharge port, whereby a predetermined 35 quantity of material within the hopper is delivered to said conveyor means upon an imperforate portion of said bottom and conveyed to said port, and means for enlarging and decreasing the size of said 40 port so as to increase or decrease the amount of material discharged therethrough.

12. A machine for feeding granulated materials in predetermined quantities, comprising a feed hopper having in its bottom 45 an elongated discharge port, a rotary circular plate overlying said bottom and having peripheral radially projecting conveyor arms, said port underlying the path of movement of said arms, whereby a predetermined 50 quantity of material within the hopper is deposited between adjacent arms successively upon an imperforate portion of said bottom and conveyed to said discharge port, and an oscillatory plate arranged between 55 said bottom and said rotary plate and having an elongated opening therein coincident with said discharge port, together with means for adjusting and securing said oscillatory plate in different positions, so as to enlarge or decrease the size of said 60

port and thereby increase or decrease the amount of material allowed to pass therethrough as desired.

13. A machine for feeding granulated materials in predetermined quantities, comprising a cylindrical feed hopper having in its bottom an elongated discharge port, a rotary circular plate overlying said bottom and having radially projecting conveyor arms, said plate being fixed on a vertical driven shaft extending upwardly through the hopper bottom and said port underlying the path of movement of said arms, a superposed fixed plate or false bottom having a centrally disposed upright circular flange and an elongated opening in its peripheral portion overlying the path of movement of said arms at a point remote from said discharge port, a hollow cone-shaped deflecting device secured on said shaft with its depending edge overlapping said flange, whereby the material within the hopper is deposited between adjacent arms successively upon an imperforate portion of said bottom and conveyed to said discharge port, and means for enlarging and decreasing the size of said port so as to increase or decrease the amount of material allowed to pass therethrough at will.

14. A machine for feeding granulated materials in predetermined quantities, comprising a cylindrical hopper having a discharge port in its bottom, a rotary conveyor overlying said bottom having peripherally projecting conveyor means, a superposed annular plate or false bottom having an opening therein overlying said conveyor means at a point remote from said discharge port, an oscillatory plate arranged between said bottom and said conveyor and adapted to close said port, said oscillatory plate having an opening therein adapted to register with said discharge port, and means for adjusting and securing said oscillatory plate in different positions, so as to open or close said port to a greater or less extent and thereby increase or diminish the amount of material discharged therethrough during each revolution of said conveyor.

15. A machine for feeding granulated materials in predetermined quantities, comprising a cylindrical hopper having an elongated arcuate discharge port in its bottom, a rotary conveyor arranged above said bottom having radially projecting conveyor arms, a superposed annular plate or false bottom having an elongated opening therein overlying said arms at a point remote from said discharge port, so as to cause the material within the hopper to enter the spaces between said arms directly over an imperforate portion of said bottom, an adjustable plate under said conveyor having an elongated arcuate opening therein registering with said discharge port, and means

for adjusting and securing said adjustable plate in different positions so as to increase or diminish the amount of material discharged during each revolution of the conveyor.

16. A machine for feeding granulated materials in predetermined quantities, comprising a cylindrical hopper having an elongated arcuate discharge port in its bottom 5 beside the inner wall thereof underlying radially projecting arms of a rotary conveyor, a superposed annular plate or false bottom having an elongated arcuate opening therein overlying the path of movement of said conveyor arms at a point remote from said discharge port, said conveyor being fixed on a vertical shaft and having an imperforate centrally disposed portion, a hollow cone-shaped deflector fixed on said shaft 10 with the depending edge thereof overlapping a marginal flange on the centrally disposed portion of said conveyor, an oscillatory plate arranged between the hopper bottom and said conveyor having an elongated 15 arcuate slot therein registering with said discharge port and means for adjusting and securing said oscillatory plate in different positions, so as to open or close said port to a greater or less extent as desired to increase 20 or decrease the amount of material that may pass through said discharge port during each revolution of the conveyor.

17. In combination, a group of feeding machines each provided with a hopper having a discharge port in its bottom, said bottom underlying a rotary feed wheel, said feed wheel being fixed on a vertical shaft depending through the hopper bottom and carrying a gear wheel in mesh with a pinion on a main driving shaft, said shaft being 25 journaled in alined bearings carried by the supporting frames of the group of machines, a fixed plate or false bottom adjustably secured above each hopper bottom and 30 having an opening therein overlying the peripheral portion of said feed wheel at a point remote from said discharge port, an oscillatory plate arranged between the hopper bottom and said feed wheel and having 35 an opening therein coincident with the discharge port in the hopper bottom, and means 40 for adjusting and securing said oscillatory plate in different positions, so as to increase or decrease the size of the discharge port for 45 delivering material from the group of machines in different proportions.

18. In combination, a group of feeding machines each provided with a cylindrical hopper having a discharge port in its bottom and underlying a rotary feed wheel having radially projecting conveyor arms, said feed wheel being fixed on a vertical shaft depending through the hopper bottom and carrying a gear wheel in mesh with a pinion 50 on a main driving shaft journaled in alined

bearings carried by the supporting frames of the group of machines, a circular plate or false bottom adjustably secured above said hopper bottom and having an opening therein overlying said conveyor arms at a point remote from said discharge port, an oscillatory plate arranged between the hopper bottom and said feed wheel and having an opening therein registering with said discharge port, and means for adjusting and 70 securing said oscillatory plate in different positions, so as to increase or decrease the size of the discharge port for delivering material from the group of machines in different proportions, said oscillatory plate carrying a swiveled lug depending through an arcuate slot in the hopper bottom, a threaded rod screwed into an opening in said lug and revolubly supported at its outer end and provided with means thereon for imparting 75 rotary movement thereto.

19. In combination, a group of machines each provided with a cylindrical feed hopper having a discharge port in its bottom and underlying a rotary feed wheel having radially projecting conveyor arms, said feed wheel being fixed on a vertical shaft depending through the hopper bottom and carrying a gear wheel in mesh with a pinion on a main driving shaft journaled in alined 80 bearings carried by the supporting frames of the group of machines, a circular plate or false bottom arranged over the hopper bottom and having an opening therein overlying said conveyor arms at a point remote from said discharge port, an oscillatory plate arranged between the hopper bottom and said feed wheel and having an opening 85 therein registering with said discharge port, and means for adjusting and securing said oscillatory plate in different positions, so as to increase or decrease the size of said port, for delivering material from the group of machines in different proportions; said means comprising an apertured lug swiveled 90 to said oscillatory plate and depending through a slot in the hopper bottom, a threaded rod screwed into the aperture in said lug and having its outer end revolubly supported and provided with means for 95 imparting rotary movement thereto.

20. In combination, a cylindrical feed hopper having an elongated discharge port in its bottom of arcuate form, a rotary feed wheel fixed on a vertical shaft extending up through said bottom, a circular plate or false bottom arranged above said feed wheel and having an elongated opening therein of arcuate form overlying the peripheral portion of said feed wheel at a point remote 100 from said discharge port, a hollow substantially conical or bell-mouth-shaped deflector 105 removably secured on said shaft and having its depending edge overlapping an annular flange on said false bottom, and means for 110

enlarging or decreasing the size of said discharge port so as to increase or decrease the amount of material passing therethrough during each revolution of said feed wheel.

21. In combination, a cylindrical feed hopper having an elongated discharge port in its bottom and a rotary feed wheel thereunder fixed on a vertical shaft, a superposed circular plate or false bottom having an im-
10 perforate portion overlying the peripheral portion of said feed wheel and provided with an elongated opening therein located at a point remote from said discharge port, and means for enlarging or decreasing the size

15 of said port so as to increase or decrease the amount of material delivered by the machine during each revolution of said feed wheel, said shaft carrying a hollow cone-shaped deflecting device having its depending edge
20 or rim overlapping an annular flange on said circular plate, said deflecting device carrying an agitating arm at its apex and agita-
25 tor arms removably secured on its lower edge or rim.

22. A machine for feeding granulated materials in predetermined quantities, comprising a cylindrical feed hopper having in its bottom an elongated peripherally dis-
30 posed discharge port, means for enlarging and decreasing the size of said port, so as to increase or decrease the amount of mate-
35 rial allowed to pass therethrough at will, a rotary feed wheel overlying said bottom and having radially projecting conveyor arms,

40 said feed wheel being fixed on a vertical shaft extending upwardly through the hopper bottom and said discharge port under-
45 lying the path of movement of said conveyor arms, a stationary circular plate or false bottom overlying said feed wheel and having a centrally disposed upright circular flange and an elongated opening in its periphery overlying the path of movement of said arms at a point remote from said

50 discharge port, and a hollow cone-shaped deflector secured on said shaft with its de-
55 pending edge or rim overlying said flange, whereby the material within the hopper is directed toward and deposited between ad-
60 jacent conveyor arms successively upon an imperforate portion of said bottom and con-
65 veyed to said discharge port, said false bot-
70 tom plate being vertically adjustable and said deflector and feed wheel being remov-
75 able and the latter interchangeable with feed wheels having conveyor arms of greater or
80 less depth, to adapt the machine for feeding in larger or smaller measure materials of different kinds.

24. In combination, a group of machines for feeding grain or other materials simultaneously in predetermined proportions, each machine having a feed wheel geared to the same driving shaft, means for mixing the materials as fed by said group, means on each machine for increasing or decreasing the amount or proportion it may feed inde-
90 pendently of other machines in the group, and means operable conjointly with the last named means on each machine for indicating the amount each machine may feed in a given period of time.

25. In combination, a plurality of machines for feeding grain or other materials simultaneously in predetermined proportions, each machine having a feed wheel geared to a main driving shaft and provided with independently operable means for increasing or decreasing the amount or proportion of material it may feed in a given period of time without changing the speed of said shaft, and means connected with and operated by said independently operable means for indicating the amount or proportion of material each machine may feed.

In testimony whereof I affix my signature in the presence of two witnesses.

SIMON SNYDER
